UNITED STATES PATENT OFFICE.

MORRIS POLLAK, OF NEW YORK, N. Y.

BRACELET.

SPECIFICATION forming part of Letters Patent No. 240,924, dated May 3, 1881.

Application filed March 11, 1881. (No model.)

To all whom it may concern:

Be it known that I, MORRIS POLLAK, of the city and State of New York, have invented an Improvement in Bracelets, of which the following is a specification.

Bracelets have been made with hinged segments and a clasp; but as this clasp is liable to become disconnected it is usual to use a guard-chain from one segment to the other. In some instances the hinge has been dispensed with and the bracelet made of sections upon elliptical spring-wires, and in other instances a thin blade of metal has been added to the clasp, the same passing into the opposite segment, and having a head to limit the distance that the bracelet can be opened.

My invention is available with the ordinary bracelet having hinged segments; and it consists in the combination, with such hinged segments, of one or more helical expansible springs and a connection passing through that spring to the opposite segment, so that the expansible spring acts upon the segments to draw them together, thus dispensing with all clasps or guard-chains, and rendering it impossible to separate the segments of the bracelet, so as to render it liable to drop off the arm and become lost.

In the drawings, Figure 1 is a section representing a bracelet with my improvement, the segments being slightly open. Fig. 2 is a separate view of the springs and connecting-strip, and Fig. 3 is a section of the hinge portion of the bracelet in enlarged size.

The segments *a* and *b* are hinged together at *c*, and these segments are to be of any desired size, shape, or material, and they may be more or less ornamented. Each section is either hollow or formed with a tubular cavity passing most of the distance around from the free end toward the hinge.

The helical springs *e* surround the connection *i*, which connection is in the form of a wire, flat strip, or chain. There are also around the wire or other connection *i* abutment-blocks *o o*, against which the inner ends of the springs press, and the outer ends of the springs are firmly connected to the connection *i* by solder

or otherwise. These parts are to be placed within the hollow bracelet, or within the cavity provided in the bracelet for their reception, and the abutment-blocks *o o* are secured into the bracelet-sections, near their moving ends. This may be done by solder, or by pinning, or in any other convenient way. The springs being always under a slight compression, they tend to close the bracelet; but if the sections are swung on the hinge so as to open them, then the wire or strip connection *i* keeps the outer ends of the helices at their uniform distance apart, and the movement of the abutment-blocks *o* with the segments of the bracelet causes the springs to be compressed; hence they will exert their force to close the bracelet as soon as liberated. The chain, strip, or wire, as the bracelet is opened, draws out of the bracelet and compresses the spring or springs, and these act by expansion to close the bracelet again.

I remark that two helical springs, one in each segment of the bracelet, are preferable; but if the necessary amount of opening movement can be obtained only one spring may be used, the other end of the strip, wire, or chain being fastened to the segment of the bracelet that does not contain any spring.

The abutment-blocks *o o* may be removed, if necessary, for repairs of the springs; or the connecting wires, strip, or chain, by withdrawing the pins or the abutments, or one of them, may be removably connected to the bracelet by passing such abutment behind fingers or catches, the spring forcing such abutment against the fingers or catches.

I claim as my invention—

The combination, with the hinged segments forming the bracelet, of a connection passing from one of the moving segments into the other, and a helical spring and abutment, substantially as specified, whereby the spring acts to close the bracelet, as set forth.

Signed by me this 5th day of March, A. D. 1881.

M. POLLAK.
